BROADHEAD HUNTING POINT

Frank Kindle and Roy Emmit Speck,
Pendleton, Ind.

Application September 20, 1930, Serial No. 483,349

6 Claims. (Cl. 273—106.5)

Our invention relates to arrow heads for arrows such as are used in wild-game hunting.

The effectiveness of arrows especially when used for this purpose, depends largely on the shape, ease of penetration, and ability of the arrow-head to cut a fairly large hole in the animal.

It is the object of our invention to improve the qualities of penetration and cutting by making the arrow head broad and thin, with its cutting edges concave, and with the thinness extending well behind the trailing points of the head so that the head may make an initial full-width cut before the shank by which it is secured to the arrow enters that cut.

The accompanying drawing illustrates our invention: Fig. 1 is a side elevation, and Fig. 2 is a plan of an arrow head embodying our invention.

Our arrow head has, in general, the conventional triangular arrow-head plan, with a point 10 and two trailing points 11; and is desirably made of a metal that will take and retain a sharp edge. Its cutting edges 12, extending between the point 10 and the two trailing points 11, are concave, and meet at a very acute angle to make the point 10 a keen one. For fastening the arrow head to the shaft, we provide at the rear of the head a shank 13, which joins the triangular portion of the head at the base thereof and desirably somewhat ahead of the trailing points 11, the edges 14 which join the cutting edges 12 to form such trailing points being angularly disposed with respect to the center line of the arrow-head for this purpose.

That portion of the shank which joins the shaft is conveniently cylindrical, and is provided on its end with a deep drilled hole 15 for the reception of the end of the shaft. The portion of the shank surrounding such drilled hole may also be provided with diametrically opposite small holes 16 for the reception of a pin to hold the shank on the shaft end.

Just ahead of the inner end of the drilled hole 15 the shank is cut away on a gradual taper until its thickness is only about half the diameter of the cylindrical portion. Conveniently, this reduced thickness is reached at or just behind a point in line with the two trailing points 11; and from there along the center line of the head to the point 10 the thickness of the head decreases.

The maximum thickness of the head in any cross section taken at right angles to the center line of the head is at that center line, and the

thickness decreases symmetrically toward the respective cutting edges 12. The greatest thickness of the triangular portion of the head is near the joint with the shank, and is desirably about one-eighth the over-all width of the head, or less; although this may be varied somewhat to insure sufficient strength for the head.

An arrow head made in accordance with our invention will thus have an extremely keen point, will be thin and broad; and this thinness will co-operate with the concave cutting edges to provide a head of easy penetration, especially for the initial puncturing of the hide of an animal. Further, the relatively thicker shank and shaft will not enter the cut until after an initial full width cut has been made, and the drag exerted by such relatively thick shank and shaft will be minimized.

An arrow equipped with a head embodying our invention will therefore penetrate deeply with less force, and will permit the use of a lighter bow with its evident advantages.

We claim as our invention:

1. An arrow head, comprising a triangular body portion and a shank integrally joined to the base thereof and adapted to be secured to the end of an arrow shaft, the sides of said body portion being sharpened to provide cutting edges, said body portion being symmetrically tapered laterally from its median line, and its greatest thickness ahead of the trailing ends of such sharpened edges being less than one-eighth ($\frac{1}{8}$) the width between the two trailing points of said head and materially less than the thickness of said shank, said shank being gradually tapered at its forward end to provide an uninterrupted surface at said joint.

2. An arrow head, comprising a triangular body portion and a shank integrally joined to the base thereof and adapted to be secured to the end of an arrow-shaft, the sides of said body portion being concave and sharpened to provide cutting edges, said body-portion being symmetrically tapered laterally from its median line, and its greatest thickness ahead of the trailing ends of such sharpened edges being less than one-eighth ($\frac{1}{8}$) the width between the two trailing points of said head and materially less than the thickness of said shank, said shank being gradually tapered at its forward end to provide an uninterrupted surface at said joint.

3. In an arrow head, the combination of a shank adapted to be secured to the end of an arrow shaft, and a cutter which is relatively thin with respect to said shank disposed wholly ahead

- of said thicker shank and integrally joined thereto, said cutter comprising a triangular blade symmetrically tapered laterally of its median line and sharpened at its edges, the greatest thickness of said blade being less than one-eighth the width between the trailing ends of said sharpened edges and approximately one half the thickness of said shank, the forward end of said shank being tapered to the thickness of the base of said blade.
5. In an arrow head, the combination of a shank adapted to be secured to the end of an arrow shaft, and a cutter which is relatively thin with respect to said shank disposed wholly ahead of said thicker shank and integrally joined thereto, said cutter comprising a triangular blade sharpened at its edges, the greatest thickness of said blade being less than one-eighth the width between the trailing ends of said sharpened edges, the forward end of said shank being tapered to 10 the thickness of the base of said blade.
10. 4. In an arrow head, the combination of a shank adapted to be secured to the end of an arrow shaft, and a cutter which is relatively thin with respect to said shank disposed wholly ahead of said thicker shank and integrally joined thereto, said cutter comprising a triangular blade symmetrically tapered laterally of its median line and sharpened at its edges, the greatest thickness of said blade being not more than approximately one-half the thickness of said shank, the width between the trailing edges of said blade being approximately four times the diameter of said shank, the forward end of said shank being tapered to the thickness of the base of said blade.
15. 5. In an arrow head, the combination of a shank adapted to be secured to the end of an arrow shaft, and a cutter which is relatively thin with respect to said shank disposed wholly ahead of said thicker shank and integrally joined thereto, said cutter comprising a triangular blade sharpened at its edges, the greatest thickness of said blade being less than one-eighth the width between the trailing ends of said sharpened edges, the forward end of said shank being tapered to 10 the thickness of the base of said blade.
20. 6. An arrow head, comprising a thin triangular cutting blade adapted to cut a full width slit in the substance into which said arrow head is projected without substantially opening such slit, a supporting shank for said blade adapted to be mounted on the end of an arrow shaft, said shank being positioned rearwardly of the cutting blade and tapered at its forward end whereby its opening of such slit will occur after the full width 20 cutting thereof.
